UNITED STATES PATENT OFFICE

168,491

COMBINED CLIP AND PENCIL HOLDER

Benjamin B. Alvarez, Mesilla, N. Mex.

Application July 29, 1952, Serial No. 20,809

Term of patent 14 years

(CL. D74—1)

To all whom it may concern:

Be it known that I, Benjamin B. Alvarez, a citizen of the United States, residing at Mesilla, State of New Mexico, have invented a new, original, and ornamental Design for a Combined Clip and Pencil Holder, of which the following is a specification, reference being had to the accompanying drawing, forming a part hereof.

I claim:

The ornamental design for a combined clip and pencil holder, as shown.

BENJAMIN B. ALVAREZ.
